UNITED STATES PATENT OFFICE.

EDWIN PRESCOTT, OF ARLINGTON, MASSACHUSETTS.

JACK.

SPECIFICATION forming part of Letters Patent No. 444,849, dated January 20, 1891.

Application filed January 28, 1890. Serial No. 338,386. (No model.)

To all whom it may concern:

Be it known that I, EDWIN PRESCOTT, of Arlington, county of Middlesex, State of Massachusetts, have invented an Improvement in 5 Jacks, of which the following description, in connection with the accompanying drawings, is a specification, like letters on the drawings representing like parts.

Prior to my invention a jack has been provided at its forward end with a wheel, the axle for the latter being fixed in the base of the jack; but in such plan the wheel and axle must be of sufficient strength to withstand the load put on the jack.

15 In my invention I have combined a wheel with the movable notched lifting-head of the jack, so that when the said member is thrown down by elevating the handle of the jack the periphery of the said wheel will occupy a 20 position below the base of the jack to run on the floor when the jack is to be moved from place to place, the lowering of the jack-handle to raise the notched lifting-head raising the wheel from the floor, the wheel in such 25 construction not being subjected to strain by reason of the load on the jack, and consequently the wheel and its axle may be very much lighter. The notched lifting-head occupies a diagonal position and is supported by 30 links at or near its upper and lower ends, one of the said links having its fulcrum at a considerable distance from the other in a longitudinal plane, such location of the fulcrum of the said links enabling the notched head to 35 be set at a very considerable inclination to thereby provide for wider notches and better engagement with the axle, and also to support the notched head more rigidly and firmly under its load, the notched head rising and falling 40 substantially perpendicularly, such inclination also enabling the horizontal parts of the notches of the jack to be of greater width than when the head is perpendicular, as in United States Patent No. 207,442, dated 45 August 27, 1878, heretofore granted to me. The perpendicular part of each notch is protected by non-metallic straps which may be of leather or rubber bent to cover the upper end of the vertical side of the notch and leave 50 an open space between the covering and the faces of the head.

Figure 1 in side elevation represents a jack embodying my invention, the dotted lines showing the lifting-head of the jack as elevated. Fig. 2 is an elevation of Fig. 1, looking at it from the left.

The base *a* of the jack has a standard *a'* and a brace *a²* rising therefrom, the standard *a'* being inclined upwardly from the front of the base toward the pivotal point for the handle *b*, which handle is inserted in a suitable iron or end piece *b'*. The brace *a²*, as herein shown, has at each side suitable brace-irons *a³*, which, as represented, are bolted to the base at 2 and are bolted through at their upper ends by a bolt 3, the said bolt serving as the fulcrum for the pair of links *c*, which are parallel, the upper end of each link being connected to the iron *b'* loosely by a bolt or ear 4. The lifting-head *d* is placed in an inclined position, as best shown in Fig. 1, and is supported by, as herein shown, a pair of links or arms *e e'*. The links *e* are pivoted at 5 and a bolt 6 is extended through the links between their ends, the said bolt entering a suitable iron or eye *e²*, attached to the lower end of the head *d*, the outer end of the links *e* receiving between them the axle or journal 7 of a wheel *f*. The pair of links *e'* have their fulcrum on the bolt 3 and are jointed at 8 to the lifting-head, and the iron *b'* has suitable pivotal connections, as 10, and as herein shown. The said pivotal connections—one at each side the handle—are jointed to a pair of irons 12, suitably secured to the lifting-head. By placing the fulcrum 5 of the link *e* at a considerable distance from the fulcrum 3 of the link *e'* with relation to a horizontal plane, it is possible to give very considerable inclination to the notched head in 85 order that the notches may be made broader to gain better hold upon the axle to be lifted, and at the same time this location of the fulcrum of the links (which location has not before been used in jacks so far as I am aware) 90 enables the notched head to be more strongly and rigidly supported, and also be moved in a substantially vertical direction. The power to raise the notched head is transferred thereto through a link connected with a lever near 95 the upper end of the notched head. The lifting-head is provided, as herein shown, with a

series of notches to form shoulders with horizontal and vertical sides, each notch being at a different height from the other notches so as to adapt the jack to carriages of different styles.

To protect the sides of the axle from injury from the vertical shoulders, I have represented the said shoulders as covered with strips of leather, or it may be rubber or other elastic material at *g*, the said strips covering the vertical sides of the shoulders and the corners at the top of the vertical sides, the covering being so placed as to leave a slight space 20 between it and the face of the notches to afford greater elasticity.

I do not herein broadly claim a cushion applied to a jack; but the specific form of cushion shown and claimed has not to my knowledge been used, nor has a cushion of the kind described been attached by metallic caps. As herein represented, I have fastened the upper end of each strip by means of a metal cap *h*, which is fitted to the horizontal shoulder and there secured in any suitable manner. When the operator engages the handle *b* and lifts it into the full line position, the head being then in its lowest position, the periphery of the wheel *f* rests upon the floor and the bottom of the base *a* is or may be a quarter of an inch or more above the floor, so that the jack may be readily rolled from place to place or rolled under the carriage to be lifted. When the handle is pushed down into the dotted-line position, the head is lifted, and while being lifted it, through suitable connections described, lifts the wheel into the dotted-line position, Fig. 1, so it will be seen that the wheel and its axle are not subjected to any of the strain put upon the jack. By inclining the lifting-head, as shown, it is possible to make wider horizontal shoulders to fit against the under side of the axle than would be practicable were the standard *a'* and the head next to it in substantially vertical position, as in the patent referred to.

In my invention it will be noticed that by placing the head in inclined position the jack when operated has substantially the same extent of movement at every shoulder, so that whether a carriage with the lowest or the highest axle adapted to be lifted by the jack is to be raised, the lift of the carriage-axle from the floor will be substantially the same.

Having described my invention, I desire to state that I believe myself to be the first to employ in connection with the jack a wheel which is lifted from the floor when the notched head is lifted to elevate an axle, and I therefore do not desire or intend to limit this invention to the exact form of device or contrivance shown for so lifting the wheel, as such construction might be varied or modified without departing from my invention.

I claim—

1. A jack having a base, a standard thereon, and a co-operating notched lifting-head, combined with a wheel and connections between it and the said notched head, the said wheel being adapted to run on the floor when the notched head is down and to occupy a position above the floor when the notched head is raised, substantially as described.

2. A jack having a base, a standard, a notched lifting-head, pivoted links connecting the lower end of the head and the standard, and a wheel and connections between it and the said notched head, whereby the said wheel may run on the floor when the notched head is down, the wheel being lifted above the floor by the upward movement of the said head when the jack is in use, substantially as described.

3. In a jack, the base, the inclined standard, pivoted links *e* and *e'*, having their fulcra thereon, one at a considerable distance from the other with relation to a horizontal plane, combined with a notched lifting-head to which the outer end of the said links are connected, and with a lever and links to connect the same with the said standard and with the said notched head, whereby the latter is raised in a substantially vertical direction, substantially as described.

4. In a jack, the notched lifting-head, combined with the non-metallic strips covering the vertical faces and upper corners of the said notches, and with metallic covering-caps placed upon the horizontal parts of the said notches, substantially as described.

In testimony whereof I have signed my name to this specification in the presence of two subscribing witnesses.

EDWIN PRESCOTT.
